UNITED STATES PATENT OFFICE.

WILLIAM W. COBLENTZ, OF WASHINGTON, DISTRICT OF COLUMBIA.

SYSTEM OF ELECTRICAL CONTROL.

Application filed September 22, 1920. Serial No. 412,050.

To all whom it may concern:

Be it known that I, WILLIAM W. COBLENTZ, a citizen of the United States of America, residing at Washington, in the District of Columbia, have invented a certain new and useful Improvement in a System of Electrical Control, of which the following is a specification.

This invention has reference to improvements in a system of electrical control, having for its object to provide a novel apparatus and method of thermal radio dynamic control of mechanisms whereby to render possible the remote control of various mechanisms possible and practical through the use of light reactive material interposed in the control circuit and adapted, with the projection of certain colors of light rays from a point distant thereonto, to have its electrical conductivity either increased or decreased whereby to vary the passage of current through the circuit and to bring about the desired operation.

Other objects will be in part obvious and in part pointed out hereinafter.

In order that the invention and its mode of application may be readily understood by persons skilled in the art, I have in the accompanying illustrative drawings and in the detailed following description based thereon, set out several practical embodiments of the same.

In these drawings:

Figure 1 is a schematic view of one possible system of thermal radio dynamic control;

Figure 2 is a similar view illustrating a modified form of control or relay circuit;

Figure 3 is a like view of another modified form of control relay circuit; and,

Figure 4 is a schematic view showing a modified form of means for projecting light rays of different colors and of greater and less lengths than 0.65 micromillimeters onto the light reactive or photo-sensitive material.

Having more particular reference to the drawings, in connection with which like characters of reference will designate corresponding parts throughout the several views, and referring in particular to Figure 1, this form of thermal radio dynamic control may

be stated to include a suitable light source 1 provided with a parabolical or other form of reflector 2 so positioned as to direct parallel light rays onto an angularly positioned condensing mirror 3 arranged at a point distant therefrom, which mirror in turn, serves to direct or reflect the light rays onto the light reactive receiver, hereinafter more fully described.

The control system also includes what may be termed a control circuit 4 or a relay circuit, in which a suitable source of energy 5 is arranged, while a light reactive substance 6 is also arranged in one side of this control circuit and is adapted to vary the passage of current through the same into an electrical responsive device 7 connected therein. This responsive device may, if desired, be in form of a galvancrometer, the indicating hand 8 of which is adapted to travel the space between the points 9 and 10, which, if desired, may serve as contact terminals for separate or individual circuits connected thereto but not shown. Hence, when the indicator is moved into contact with either of these terminals 9 or 10, the same will serve to close the particular electrical circuits in which the same are arranged. Of course, it is not my intention to limit myself to this particular embodiment or to any other specific adaption of my improved system of control, the underlying principle of the invention residing in the provision of an electrical system of remote control, that is, a system whereby various mechanisms located at a distance from a source of light may have their operations controlled by the operator who is positioned in proximity to or adjacent such light.

The light reactive body 6 is preferably formed of molybdenite or sulphide of molybdenite, although other forms of photo-sensitive or light reactive materials may be employed, such as conditions or preference may dictate, as for example, sulphide of antimony or selenium or stibnite.

To permit the desired coloring of light rays emitted from the light source 1, I employ a plurality of transparent colored screens, one of which is shown in Figure 1 and indicated by the numeral 11. This screen 11 is adapted to cover the light source

- 22
- 1 and by reason of its coloring which may be either violet, blue, green, greenish yellow, or yellow, will serve as means for absorption of light rays of wave lengths greater than 65 0.65 micromillimeters. The light rays so screened when directed onto the light reactive body 6 by means of the angularly positioned condensing mirror 3 will serve to decrease the electrical conductivity thereof 70 and in consequence, will decrease the flow of current through the electrical responsive device 7 connected in the control circuit 4 whereby to effect variation in the positions 75 of the indicator 8 or the return of the same 10 to its initial starting position whereat it will contact with the terminal 10. To increase the electrical conductivity of the body or receiver 6, a second screen, not shown, is substituted in lieu of the screen 11 and will 80 serve to transmit only light rays of wave lengths greater than 0.65 micromillimeters. This second screen is preferably in form of a ruby glass or the like. Thus, with the ruby screen covering the light source 1, the 85 20 electrical conductivity of the receiver 6 will be increased, again varying the flow of current through the control circuit 4 and the electrical responsive device 7 connected thereto in order that the indicator 8 will be 90 25 moved from its initial starting position adjacent the terminal 10 into contact with the terminal 9 for closing the second circuit of the mechanism to be controlled by my improved system. 95 30 Instead of employing a body of light reactive material such as indicated at 6 in the Figure 1, I have found it practical to also include in the control circuit 4 in lieu thereof, a Wheatstone bridge indicated in its entirety by the numeral 12 having a body of light reactive material 13 in one arm thereof, as clearly shown in the Figure 2. A galvanometer 14 or other electrical responsive device is connected at opposite points to the 100 40 arms of the bridge and has contact terminals 15 and 16 positioned upon either side of and in proximity to the indicator 17 of such galvanometer. 105 45 In employing the arrangement shown in Figure 2, the Wheatstone bridge 12 is positioned in such a manner as will permit the reflection of the colored light rays onto the light reactive body or receiver 13. Starting with the bridge 12 balanced in 110 55 the dark, the galvanometer indicator will be caused to swing, say in the direction of the contact terminals 15, whereby to close the circuit in which the same are interposed when the receiver 13 is exposed to red or infra red radiation, that is, light rays of wave lengths greater than 0.65 micromillimeters. However, when the receiver 120 60 is exposed to light rays of violet, blue, green, greenish yellow, or yellow, or rays of wave 115 lengths shorter than 0.65 micromillimeters, its electrical conductivity is decreased and in consequence, the flow of current therethrough will be shunted through that path of travel afforded by that arm of the bridge affording the least resistance, whereby to 120 effect the passage of the current through the galvanometer 14 in an opposite direction in order that the indicator 17 thereof will be moved in an opposite direction, that is, into engagement with the contact terminals 16 for closing the particular circuit in which they are interposed. 125 As another modification of the form of the invention shown in Figure 2, I may employ two light reactive receivers such as 130 indicated at 18 and 19 in Figure 3, these receivers being arranged in the opposite arms of the Wheatstone bridge 12' which is included in the control or relay circuit 4; the opposite sides of a galvanometer 14' or other desired electrical responsive device being connected to such opposite arms of the bridge as clearly shown. By this multiple arrangement, it of course will be understood that the sensitivity of the regulating device will be doubled, the receivers 18 and 19 decreasing in electrical conductivity upon the projection of light rays of wave lengths less than 0.65 micromillimeters 135 thereonto and increasing in their electrical conductivity with the projection of light rays of wave lengths greater than 0.65 micromillimeters, these several actions of the receivers, obviously, causing the flow of current through the arms of the bridge to be 140 changed in direction and to enter the galvanometer 14' in directions which will cause, optionally, the movement of this indicator 17' into engagement with either the contact terminals 15' or 16' for closing the particular electrical circuits in which they are interposed. 145 In lieu of the form of light projecting means as schematically shown in Figure 1, it has also been found practical to employ that form of apparatus which is also schematically shown in Figure 4, comprising a light source 20, the rays from which are received and collimated by a lens 21 of a spectroscope, whereupon the same are dispersed by direct vision prism 22 and then focused into a spectrum 23 by means of an image forming lens 24 of the spectroscope. An angularly adjustable mirror 25 is positioned in proximity to the image forming lens 24 of the spectroscope and by moving the same to one position, the red rays from the spectrum will be reflected therefrom through a lens 26 in order that the same 150 will be projected in parallel onto the light reactive means of the control circuit 4, while when the mirror 25 is shifted to its second position, the yellow light rays from the 155 160

spectrum 23 will be reflected therefrom through the lens 26 in parallel onto said light reactive means. By this circuit reflection of light rays of wave lengths greater and less than 0.65 micromillimeters, it is to be understood that increasing or decreasing of the electric conductivity of the light reactive receiver arranged in the control circuit 4 may be controlled at will by an operator merely with the shifting of the mirror 25 to the desired position.

For purpose of illustration, it may be stated that the circuits controlled by the indicator of the galvanometer or the other movable element of whatever form of electrical responsive device is employed with the control circuit 4 may be adapted to operate motors in opposite directions in the steering of a torpedo from a remote distance, or other mechanism, such as relays, recording devices, etc.

It is to be also understood, that I do not confine my invention to a single light reactive receiver or bridge, but that various modifications of the apparatus or construction herein shown may be resorted to and that such modifications as are within the scope of my claims I consider within the spirit of my invention.

I claim:

1. A method of thermal radio dynamic control consisting in the optional projection of thermal rays of wave lengths greater than 0.65 micromillimeters or less than 0.65 micromillimeters onto a light reactive receiver interposed in a relay circuit, whereby to increase or decrease the electrical conductivity of said receiver to vary the flow of current through an electrical responsive device connected in such circuit.

2. A method of thermal radio dynamic control consisting in the directing of rays of thermal radiation onto a photosensitive body interposed in a relay circuit for either increasing or decreasing the conductivity of said body dependent upon the intensity and wave length of such rays for causing operation of an electrical responsive device interposed in the relay circuit.

3. A method of thermal radio dynamic control consisting in the projection of rays of thermal radiation onto a light reactive body interposed in a relay circuit, the source of such thermal rays being at a point remote from the light reactive body whereby to increase or decrease the electrical conductivity of such light reactive body to effect operation of an electrical responsive device connected to the relay circuit, and a modulation of the thermal rays adjacent the source thereof for either increasing or decreasing their intensity and wave lengths.

4. A thermal radio dynamic control apparatus comprising a light source, an elec-

tric relay circuit remote from such source, an electrical responsive device in the relay circuit, photosensitive means interposed in one side of said circuit adapted to receive the light rays emitted by said source, and means for modulating the light rays emitted by such source to vary the intensity and wave length thereof to increase or decrease electrical conductivity of the photosensitive means dependent upon their wave lengths.

5. A thermal radio dynamic control apparatus comprising a light source, an electric relay circuit remote from said source, an electrically responsive device interposed in the circuit, a photosensitive body in one side of such circuit adapted to have the rays emitted by said source directed thereonto, and means for selectively coloring the light rays emitted by said source whereby to vary the intensity and wave length thereof for effecting increase or decrease in the electrical conductivity of said body.

6. A thermal radio dynamic control apparatus comprising a light source, an electric relay circuit remote from such source, a Wheatstone bridge in the circuit having certain of its arms formed of a photo-sensitive material and adapted to receive the light rays emitted by said source, an electrically responsive device connected to the bridge, and means for selectively changing the intensity and wave length of the rays of thermal radiation emitted by said light source whereby to increase or decrease the conductivity of the photo-sensitive material.

7. A thermal radio dynamic control apparatus comprising an electric relay circuit, a Wheatstone bridge in the circuit, certain of the arms of said bridge being formed of molybdenite and adapted to receive light rays emitted by said source, an electrically responsive device connected to the bridge, and means for selectively changing the thermal rays emitted by the light source whereby to increase or decrease their intensity and wave lengths for varying accordingly, the electric conductivity of said molybdenite arms.

8. A thermal radio dynamic control apparatus comprising a light source, an electric relay circuit remote from such source, a Wheatstone bridge in circuit, one of the arms of said bridge being formed of a photo-sensitive material and exposed to the action of the light rays emitted from said source, an electrically responsive device connected to the bridge, and means for selectively changing the intensity and wave lengths of the thermal rays emitted by the light source whereby to increase or decrease, accordingly, the electric conductivity of the molybdenite arm.

9. A thermal radio dynamic control apparatus comprising a light source, an elec-

tric relay circuit remote from such source, a Wheatstone bridge interposed in the circuit, certain of the arms of said bridge being formed of molybdenite adapted to be exposed to the action of rays from said light source, an electrically responsive device connected to the bridge, and means adjacent

such light source for selectively coloring the rays emitted therefrom whereby to change the intensity and wave lengths of the same to accordingly increase or decrease the electrical conductivity of said molybdenite arms. 10
